PLUMBING FITTING ASSEMBLY

Alexis C. Engelheart, Houston, Tex.

Application January 4, 1946, Serial No. 639,013

2 Claims. (Cl. 4—311)

1

The invention relates to a piping system fitting and more especially to a fitting for plumbing systems.

The primary object of the invention is the provision of a fitting of this character, wherein it has connection with a sewerage piping, and enables the association therewith of a group of fixtures such as, a lavatory, kitchen sink and a toilet bowl, or the like, as well as a shower drain, the fitting being of novel construction and is unique in the arrangement thereof, as the toilet bowl can be readily and conveniently attached thereto, with sewerage connections from all of such fixtures, without excessive piping for such purpose.

Another object of the invention is the provision of a fitting of this character, wherein it can be arranged so that access can be had thereto for the cleaning out of the connections with ease and dispatch, to avoid stoppage in the system, it being readily installed and is serviceable for many drains.

A further object of the invention is the provision of a fitting of this character, which is simple in construction, thoroughly reliable and efficient in its purposes, strong, durable, conveniently installed within a building and inexpensive to manufacture and install.

With these and other objects in view the invention consists in the features of construction, combination and arrangement of parts as will be hereinafter more fully described, illustrated in the accompanying drawing, which discloses the preferred embodiment of the invention and pointed out in the claims hereunto appended.

In the accompanying drawing:

Figure 1 is a side elevation of the fitting constructed in accordance with the invention;

Figure 2 is a top plan view thereof, it being in full lines while by dotted lines are disclosed various fixtures in associated relation thereto.

Figure 3 is a fragmentary elevation showing a portion of the fitting with the clean out plug.

Figure 4 is a sectional view taken on the line 4—4 of Figure 1 looking in the direction of the arrows.

Similar reference characters indicate corresponding parts throughout the several views in the drawing.

Referring to the drawing in detail, the fitting constituting the present invention, comprises a vertically disposed straight stand pipe section 10, having at its uppermost end the usual hub portion 11 for the joining thereof with a continuation pipe section (not shown) upwardly of a house

2

for a plumbing system therein. The lower end of this section 10 is adapted for coupling with a main waste or soil pipe layout which also is not shown.

5 Cast or otherwise integrally formed with the section 10 is a horizontally directed laterally extending substantially triangular shaped piping frame involving the upper and lower spaced outwardly converging portions 12 and 13 respectively, 10 which open into the section 10 at their inner ends next thereto, and the union bend 14 at their outermost ends.

Within the frame crosswise thereof and joined with the portions 12 and 13 are perpendicular 15 pipe runs 15 and 16, respectively which are substantially parallel with the stand pipe section 10 while the run 15 has at diametrically opposite sides thereof vertically aligned webs forming wings 17, which are provided with open slots 18 20 opening through the outer free edges thereof.

The lower portion 13 bend 14 and runs 15 and 16 are provided with proper sized nipples 19 respectively so that drain or waste leads, not shown, can be tapped therein from a kitchen sink 25 diametrically shown and indicated at 20, as well as a lavatory basin, toilet bowl and a shower stall 21, 22 and 23 respectively as best seen in Figure 2 of the drawing.

The bowl 22 is adapted to be connected to the 30 webs or wings 17 in any suitable manner for the mounting thereof on the piping frame, hereinbefore mentioned, the slots 18 being for the fasteners, not shown, effecting the mounting of such bowl.

35 The pipe section 10 is formed with a coupling branch 24 and a clean out portion, the latter being closed by a removable plug 25, while the branch 24 is for a take-off of the plumbing system to other localities of a house. The fitting 40 can be installed in any selected manner within the walling of a house or the like and at any floor plane thereof.

What is claimed is:

1. An integral fitting comprising a vertical 45 standpipe, a one-piece pipe bent back upon itself forming a bight pipe portion and upper and lower pipe portions diverging therefrom, said upper pipe portion being in communication with and extending laterally from said standpipe in a substantially horizontal direction, said lower pipe portion being in communication with and extending laterally from said standpipe at an angle thereto, said pipe portions being integrally joined to said standpipe whereby a unitary structure is formed, a plurality of pipe runs extending be-

tween and in communication with said upper and lower pipe portions, said pipe runs being spaced from and extending substantially parallel to each other and to said standpipe, said one-piece pipe, said pipe runs and said standpipe being coplanar, and a plurality of nipples extending from said pipe runs, said bight portion and said lower pipe portion for connection to waste outlets of plumbing fixtures.

2. The combination of claim 1 and wing portions integrally formed with and extending transversely from diametrically opposed portions of one of the parallel pipe runs and in the plane thereof, said wing portions adapted to support a plumbing fixture for connection to a nipple on 10 said one of the parallel pipe runs.
